UNITED STATES PATENT OFFICE.

HARRY L. ADAMS, OF PHILADELPHIA, PENNSYLVANIA.

PENCIL-SHARPENER.

1,083,649.

Specification of Letters Patent.

Patented Jan. 6, 1914.

Application filed June 13, 1910, Serial No. 566,617. Renewed May 16, 1913. Serial No. 768,155.

To all whom it may concern:

Be it known that I, HARRY L. ADAMS, a citizen of the United States, residing in Philadelphia, Pennsylvania, have invented 5 certain Improvements in Pencil-Sharpener, of which the following is a specification.

My invention relates to means for sharpening or pointing the leads of pencils; and the object of my invention is to provide a 10 simple and efficient device for accomplishing this work, which device may form an independent structure to be carried in the pocket or may be carried at the end of an ordinary pencil prepared for the purpose of receiving 15 the same, or at the end of a holder supporting a pencil or a section or sections of pencil lead. These and other features of my invention are pointed out hereinafter, reference being had to the accompanying drawings, in which:

Figure 1, is a perspective view of my improved pencil sharpener or pointer in the position of use; Fig. 2, is a sectional view illustrating the carrier for the pencil pointer 25 with the latter in position; Fig. 3, is a perspective view of the pencil pointer and its carrier detached; Fig. 4, is a plan view of the pencil pointer; Fig. 5, is a perspective view of blanks from which the pencil pointers may be made; Fig. 6, is a view illustrating 30 a step in the manufacture of pencil pointers embodying my invention, and Figs. 7, 8, 9 and 10, are views of other forms of sharpening or pointing members embodying 35 my invention.

The essential feature of my invention comprises a bit or stock having a plurality of cutting or shaving edges to engage the pencil lead. This bit or stock comprises a 40 shank 1, having a groove or grooves 2, and when two grooves are employed they are preferably disposed upon opposite sides of the shank and substantially opposite each other, but preferably slightly offset with respect 45 to each other in a manner and for a purpose hereinafter described. The end of the bit may be milled or otherwise notched to form a long beveled slit in a direction substantially at right angles to the plane of the 50 groove or grooves formed in said bit, and such construction provides a plurality of

cutting edges; the working end of the bit showing substantially V-shaped spaces wide at the outer end and tapering substantially to a point at the root of the notch or notches. 55 In the preferred form of structure embodying my invention as shown in Figs. 1, 2, 3, *et seq.*, the bit is provided with four cutting edges; two of which are indicated at 3, and two at 4. An important feature in the arrangement of these cutting elements is the fact that their active edges are not disposed in an annular or circular path, and hence in practice not more than two of the cutting edges come into active contact with the lead 60 to sharpen the same at any one time; the non-acting edges acting as guides, and when one set is cutting the other is guiding and vice versa. By this means there is no danger of the pencil lead jamming and breaking 65 while being pointed or sharpened, or making flat places on the pencil point. This feature is clearly brought out in Figs. 4 and 5, and an examination of these views will reveal that each groove in the blank is so 70 disposed as to leave a relatively wide edge 5 on one side and a relatively narrow edge 6 on the other; such disposition being on each side of the blank in such relation that the wide edges are opposite the narrow 75 edges. By this means, the differently spaced cutting elements may be formed, as clearly indicated in Fig. 4, by the use of a suitable tool, such as a milling cutter 7 as indicated in Fig. 6, so arranged as to cut through the 80 end of the blank in a line substantially at right angles to the plane of the grooves; the 85 roots of said grooves not being directly opposite each other.

In the structure shown in Fig. 7, the cutting elements have been spread slightly by a suitable tool inserted between the same. This spreading effect may be in both directions or at right angles to the cut. In the structure shown in Fig. 8, the blanks from 90 which the cutting devices are made have only one groove. A cut is made across the end of the bit at right angles to this groove, such cut forming a pair of cutting elements 3^a and 4^a, and a guide member 8. The cutting elements 3^a and 4^a may be spread 95 slightly to insure a space of proper size and 100

contour to effect the desired pointing or sharpening of the pencil.

In the structure shown in Figs. 1, 2, 3, *et seq.*, the groove or grooves 2 are substantially V-shaped.

In Fig. 9, I have shown a cutting device in which the grooves are rounded as indicated at 2^a; such grooves being offset with respect to each other on opposite sides of the shank 10 or bit.

In practice, it is desirable that the groove or grooves of the shank or bit extend the full length of the same since such arrangement permits the preparation of the shanks 15 or bits in stock lengths, and in some instances with the grooves rolled therein, or cut as may be desired. However, as the grooved condition is only needed at the active cutting end of the bit, I may provide a bit of 20 the character shown in Fig. 10.

When the bit has been notched by a milling tool or other device it may be desirable to finish the active edges of the cutting elements by means of a small oil stone or the 25 corner of the same working in the grooves of the bit.

I preferably organize my structure by providing a suitable holder 9 having a removable end or cap 9^a, and place the sharpening or pointing element in such cap. To hold it in place, I provide a suitable chuck 10 which may be made of metal tubing shaped to conform to the contour of the bit and held in place by suitable means, such as 30 a pin 11. If desired, the cap 9^a may have a knurled edge 12 to facilitate turning and may be provided with a rubber tip 13 for erasing purposes.

Other forms of cutting or pointing devices 40 may be made within the scope of my invention; the essential point being the provision of a grooved and notched bit forming a plurality of cutting edges so arranged that while some are cutting the others act as 45 guides and vice versa.

I claim:

1. A pencil pointer comprising a member having a plurality of angular projections with cutting edges, said edges being in pairs 50 offset with respect to each other, and each pair of said projections having beveled faces paralleling each other and each projection also having a face intersecting a beveled face to form a cutting edge.

55 2. A pencil pointer comprising a grooved member having a plurality of projections with cutting edges, formed by notching said grooved member substantially at a right angle to the plane of the grooves, said edges 60 being offset with respect to each other.

65 3. A pencil pointer comprising a member having paralleling outer walls with a plurality of projections with inwardly disposed cutting edges extending diagonally with respect to the outer walls, one of said edges

being offset with respect to a circular arc passing through the planes of the other cutting edges.

4. A pencil pointer comprising a grooved member having paralleling outer walls with 70 a plurality of projections with inwardly disposed cutting edges extending diagonally with respect to the outer walls, one of said edges being offset with respect to a circular arc passing through the planes of the other 75 cutting edges.

5. A pencil pointer comprising a longitudinally grooved member notched in the end at substantially right angles to the plane of the grooved portion to form a plurality of 80 cutting edges.

6. A pencil pointer comprising a member having grooved walls in a plurality of planes, said member being notched at the end substantially at right angles to the plane 85 of said grooves to form a plurality of cutting edges, said notch being V-shaped and forming cutting edges diagonally disposed with respect to the plane of the grooves.

7. The combination with a holder, of a 90 grooved member carried thereby, and a grooved pencil pointer adapted to be carried by said holder, the grooves of the pencil pointer being substantially of the same character as the grooves in the holder.

8. The combination of a pencil casing having a hollow end, a plug fitting the end of said casing, a pencil sharpener carried by said plug comprising a bit having grooved sides with a plurality of sharpening elements, and a grooved chuck carried by said plug in which the said sharpening bit is removably held.

9. A pencil pointer comprising a metal bar or bit having two parallel beveled or 105 V-shaped grooves on substantially opposite sides, with a comparatively long concaved or V-shaped notch in end of said bit or bar substantially at a right angle to said parallel beveled grooves, the structure so made forming, without any subsequent opening or spreading, a plurality of tapering blades having chisel shaped cutting edges.

10. A pencil pointer comprising a member having a plurality of projections with cutting edges, said edges being in pairs offset with respect to each other and each projection having a plurality of faces forming a cutting edge at their intersection, one of said faces paralleling a corresponding face on the projection diagonally opposite, while the other face parallels a corresponding face on the adjoining projection.

11. A pencil pointer comprising a member having a plurality of projections with angular cutting edges, said edges being in pairs offset with respect to each other, and the projections carrying said edges differing in size.

12. A pencil pointer comprising a member 130

having a plurality of projections with angular cutting edges, said edges being in pairs offset with respect to each other, the projections carrying said edges differing in size, 5 with the projections diagonally opposite each other of substantially the same size.

In testimony whereof, I have signed my

name to this specification, in the presence of two subscribing witnesses.

HARRY L. ADAMS.
